UNITED STATES PATENT OFFICE.

ORVILLE F. SHATTUCK, OF INDIANAPOLIS, INDIANA.

DOOR CARRIER.

Application filed October 17, 1925. Serial No. 63,106.

To all whom it may concern:

Be it known that I, ORVILLE F. SHATTUCK, a citizen of the United States, and a resident of Indianapolis, county of Marion, and State of Indiana, have invented a certain new and useful Door Carrier; and I do hereby declare that the following is a full, clear, and exact description thereof, reference being had to the accompanying drawings, in which like numerals refer to like parts.

The object of this invention is to improve the construction and operation of means for mounting a door for a structure, and a carrier for releasably engaging the door, detaching it, moving it laterally to another position and replacing it in closed position.

The invention is made with particular reference to lumber dry kilns and other structures, such as shops and garages, where a plurality of doors is required for a plurality of door openings, and it is necessary that each door may not only be opened but moved laterally out of the way of the door opening, or moved to another door opening. To that end a single track rail is secured to the structure above the plurality of door openings, and a single carrier or frame is adapted to travel on said track and pick up any door and move it away and replace it in door-closing position.

One feature of the invention consists in improved means for suspending the door in closing position so it will hug tightly to the wall of the building, by securing to the top of the door a plurality of door hanger fixtures, preferably in loop form, each adapted to engage an outward leg and upwardly inclined hanger hook on the track fixture, which is in the form of a plain arm of a width appreciably less than the width of the door hanger, so as to avoid any niceties and difficulties in closing the door and removing the same. Heretofore the fixtures for accomplishing this work have been complicated and difficult to operate because they were close fitting and in fact required an accurate and wedging fit that made it difficult to close a door and even to open it and required great care.

Another feature of the invention consists in providing a plurality of fixtures on, outside of, and near the top of the door, having a plain plate with an elongated notch or recess in its lower edge; and providing a car-

rier with a corresponding plurality of lifting arms, each having a relatively thin projection or hook adapted to engage the plate on the door in said elongated recess, whereby the carrier can with ease engage the door and pick it up very rapidly and quickly for transporting the same. Heretofore, the door lifting fixtures also have been so made as to require relatively close fitting and great pains in operating the same so as to cause said fixtures to properly cooperate.

With these and the other improvements herein set forth and claimed, the operation of such door carriers and the removal, transportation and replacement of the doors, especially metal doors, is greatly facilitated. Much less care and pains is required and, therefore, the operations can be made very rapidly and without any failures in the operations.

The full nature of the invention will be understood from the accompanying drawings and the following description and claims:

In the drawings, Figure 1 is a perspective view of dry kiln doors and associated parts, parts being broken away and the doors in closed position. Fig. 2 is a side elevation of a door in closed position, and a carriage for lifting it out of and moving it into closing position, and parts with which the door is connected shown in vertical section, the open and supported position of the door and the carriage being shown by dotted lines. Fig. 3 is a perspective view of the upper part of a door with one form of lifting plate and hanger bar, parts being broken away. Fig. 4 is a vertical section through the upper part of a metal door, a track and track fixture and the portion of the structure to which the track and door are connected, the track and a side elevation of one form of track fixture and of the upper portion of a lifting arm, parts being broken away. Fig. 5 is a front elevation of a part of the track, a track fixture and hanger hook, the upper part of a door, and a hanger bar, parts being broken away. Fig. 6 is a central vertical section through the upper part of a door, showing an integral form of hanger bar and lift plate construction. Fig. 7 is a vertical section through the upper part of a wooden door, and of a lift plate and hanger bar construction suitable therefor. Fig. 8 is

a left-hand elevation of the upper part of Fig. 7 with parts of a hanger hook, parts being broken away.

We will suppose that there is a dry kiln or like construction having a wall 10 with a plurality of doors 11, three being shown in Fig. 1, for closing door openings located between uprights or door jambs 12. Railway track rails 13 are shown on the floor along which cars loaded with lumber or the like, not shown, are moved into and out of the dry kiln, through said door openings. Said doors are required to be individually opened and moved laterally out of the way of a car as it is moved into or out of the kiln. This is done by the following mechanism:

The structure preferably has along the top of the door openings a strong beam 15 extending horizontally and preferably in the form of a metal angle bar, as shown in Figs. 1 and 6. There is also a horizontal track rail 16 secured to the building at a point just above the door openings, as shown in Fig. 1. This track rail has the general shape of a T-railway rail of ordinary type, but it is mounted in a horizontal instead of a vertical position, as shown in Fig. 6. This is done by a track fixture 17 that is secured to the dry kiln structure and preferably to the beam 15 by bolts 18, as shown in Fig. 4. This fixture has an upper arm projecting outwardly with a track receiving clamping head 19 thereon adapted to receive the lower edge of the base of the track rail 16 and the upper edge of said track rail is held by a bracket jaw 20 that is secured in place by a bolt 21 which extends through the bracket jaw and around a tubular portion 22 of the track fixture 17. There are preferably two of these track fixtures over each door opening, but the track rail 16 is continuous for the whole series of doors. Three doors are shown herein, but the number may be greater or less, as desired. The track fixture has a hanger hook 23 at the lower end thereof, as shown in Fig. 4, upwardly and outwardly inclined, on which the door is supported in closed position, as shown in Figs. 1, 2 and 4.

The door 11, in the form shown in Fig. 4, is a metal door having a front plate 25 across the upper end and a rear plate 26 and an angle bar 27 at the upper right-hand corner. To the plate 25 or upper front part of the door there is secured a lift plate 28 by bolts 29. It has a rearwardly extending projecting plate 30 that extends under the upper member of the angle bar 27. The hanger fixture 31 is secured to the top of the door, it having a bottom through which a bolt 32 extends and secures it to the angle bar 27 and the horizontal plate 30, and said hanger fixture is secured to the upper end of the plate 28 by a bolt 33. The fixture 31 has a horizontal hanger bar 34 adapted to engage and be supported by the hanger hook

23 of the track fixture 17. There are two of the hanger fixtures 31 on the door and they are supported by two of the hanger hooks 23 and in that manner the door is hung or held suspended and in closing position, as seen in Figs. 1, 2 and 4.

The door is disengaged from the structure and opened and held open and supported on the track rail 16 by a carrier, as shown in Figs. 1 and 2. This carrier has a frame 40 formed substantially as shown in Fig. 1, of parallel side bars arranged V-shaped at the lower end and rigid connecting rods 41 and 42 and top rods 43 and 44. There is also a vertical rod 45 at the lower end of the carriage frame extending from the horizontal rod 41 down to the lower apex of the frame. This carriage frame is supported on the track rail 16 by brackets 46 and flanged rollers 47 which are mounted in said brackets. The brackets are secured between the upper ends of the parallel side bars 40 of the carriage frame by means of the two rods 43 and 44. The lower end of the carriage frame is held in place with relation to the door by a link 48 on the frame and a hook 49 on the door, as shown in Fig. 2.

The door is picked up and supported by lifting arms 50 which are fulcrumed between the parallel side bars 40 of the carrier frame at 51, as seen in Fig. 2, and each lifting arm has at its upper end a finger 53 projecting rearwardly and adapted to be inserted under the lift plate 28 in a groove 54. A lever 55 is pivoted to the upper end of the lifting arm 50 at 56 and to the upper end of a triangular frame 57. This frame consists of three rods, the upper one horizontal and the two side rods extending outwardly and inwardly and slidably connected with the vertical rod 45. There is also a lever 60 pivoted to the upper end of said triangular frame at 61 and to the parallel side bars at 62 slightly above the pivotal point 51 of the lifting arm 50. With this construction, when the triangular frame 57 is forced downward from the position shown in Figs. 1 and 2, you can lift the door off the hanger hooks 23 upwardly and outwardly to the dotted line position shown in Fig. 2. The downward movement or operation of said triangular frame is effected by a hand lever 65 which is pivoted at one end at 66 to the lower part of the carrier frame and between the ends of said lever 65, it is connected by the connecting bars 67 with the lower end of the triangular frame 57. The downward movement of the hand lever 65 will cause a downward movement of the triangular frame 57 to bring it into the dotted line position shown in Fig. 2, and that will lift the door off its supports, and then the door will be supported by the carrier on the track rail 16, and the door can then be moved laterally on said track rail to either side as far as desired.

When it is desired to close the door, it is caused to travel on said track rail laterally to a position in front of the door opening and then the hand lever 65 is moved vertically so as to cause an operation of the members of the carriage opposite to that during the opening movement of the door, which causes the door to be moved inward toward the structure, so that the hanger bars 34 will 10 pass over the hanger hooks 23 and then the weight of the door and inclination of said hanger hooks 23 and hanger bars 34 will cause the door to slide inwardly against the structure and hold it tightly in closed 15 position.

Each door has in its lateral edge a laterally-extending pin 70, as shown in Fig. 2, that is adapted to enter a notch in a plate 71 secured to the door jamb 12. The plate 20 71 at the bottom of the notch therein has a downwardly and inwardly inclined surface 72, so that the weight of the door acting through the pins 70 and the inclined notched surface 72 will cause the middle part of the 25 door to wedge downwardly and inwardly to a tight closing position.

There is a general door support having no relation to the carrier heretofore described, to be seen in Figs. 1 and 5. It is midway 30 between the rail fixtures 17 and it consists of a vertical fixture 75 that is clamped on the rail 16 by a clamp 76 and is secured to the frame beam 15 by bolts 77 and has a hanger hook 23 similar to that on the track 35 fixture 17. A hanger fixture 78 is secured to the top of the door by bolts 79 and it has a horizontal hanger bar 80 which is adapted to move in over and slide down on the hanger hook 23 when the door is moved to 40 closing position, the same as happens with reference to the hanger bars 34, and the hanger hooks 23 in the structure heretofore described.

It is to be noted that the hanger hooks 23 45 are single arms projecting upwardly and outwardly from the fixed part of the structure and are relatively narrow, while the hanger bars 34 and 80 are very wide, several times the width of the hooks 23. Likewise 50 the recess 54 in the lower edge of the lift plate 29, see Fig. 3, is very wide, while the upper end of the lifting arm 50 is relatively very narrow, as compared with the width of the recess 54 in the plate 29. Likewise there 55 is a long recess 81 in the upper end of the lifting arm 50. These and the other features of the construction are such as to enable the door to be readily picked up and moved to an open position, and likewise return to 60 closing position without any niceties of operation and without taking any particular pains and care, such as has been required by similar apparatus heretofore. With a number of doors in line and rapid action 65 required for opening and closing and mov-

ing them, it affords a great saving of time and expense for the door construction to be such that when the parts are moved into approximately proper positions, they will engage each other and operate satisfactorily. 70

Thus the fingers of the lifting arm 50 do not have to be located in any particular place in the slot 54 under the plate 29, nor does the hanger bar 34 require to be located 75 in any particular place on the hanger hook

23. This enables rapid and satisfactory operation of such apparatus to be accomplished. It also enables the apparatus to satisfactorily operate regardless of defective 80 constructions or warping or any other slight irregularity in the form or arrangement of any of the parts of the apparatus. This is particularly important in metal doors which expand materially and warp under the influence of the heat and cold and of wooden 85 doors which are affected materially by moisture and dryness.

Fig. 6 shows a modified form of the upper end of the door where the lift plate 28 and bar 30, hanger fixtures 31 and hanger bar 90 34, are all integral.

A modified arrangement is shown in Figs. 7 and 8, relative to wooden doors on lift plates 28 being provided with a horizontally rearwardly extending plate 30, and there is 95 a hanger strap 85 which at its upper end is secured to the hanger fixture 31 and plate 28 by a bolt and nut 86. The rear end of the hanger strap 85 is bifurcated, as seen in 100 Fig. 8, and the two legs thereof are secured to the rear part of the door by the bolts 29. This makes a very strong construction for mounting said fixtures on the wooden doors.

The hanger hooks 23 are preferably integral with the track fixtures 17, as shown, in 105 order that the relation between the hook 23 and the rail 16 may be at all times maintained. While the hook 23 may be separate from the track fixture 17, that would render 110 it more difficult to maintain the exact relationship between the hook 23 and the track rail 16. Unless this relationship be maintained, the hanger bars 34 at the top of the doors would not always register with the 115 hooks 23 in closing the door. Also in this device there is a fixed relation between recess 54 in the bottom of the lift plates 28 and the track 16 and hanger hooks 23, so that the carrier can always replace and remove the 120 hanger bars 34 on and from the hanger hooks 23. This fixed relation is due to plates being 125 fastened to the hanger bars 34.

The invention claimed is:

1. The combination with a structure having a door opening, a removable door, a track extending horizontally above the door opening, and a detachable carriage travelling on said track and adapted to pick up the door and support it while open and return it to closing position, of relatively wide hanger 130

bars secured to the top of the door, and relatively narrow upwardly and outwardly extending hanger hooks secured to the structure in position to receive the hanger bars and support the door, substantially as set forth.

2. Apparatus substantially as set forth in claim 1, with track fixtures secured to the structure for supporting the track, and said hanger hooks being rigidly secured to said track fixtures.

3. The combination with a structure having a door opening, a removable door, a track extending horizontally above the door opening, and a detachable carriage travelling on said track and adapted to pick up the door and support it while open and return it to closing position, hanger fixtures secured to the top of the door and each having upwardly extending sides and a relatively long hanger bar extending between the sides thereof to form a loop-like hanger fixture, and relatively narrow upwardly and outwardly extending hanger hooks secured to the structure in position to receive and support the hanger bars of the door, substantially as set forth.

4. Apparatus substantially as set forth in claim 3, with the bottom surface of the hanger bars being flat and upwardly and outwardly inclined like the hanger hooks.

5. Apparatus substantially as set forth in claim 3, with the hanger fixture having a bottom plate adapted to rest upon the door, and means for securing it on the top of the door so as to prevent rocking displacement on the door.

6. The combination with a structure having a door opening, a removable door, a track extending horizontally above the door opening, a carriage traveling on said track and having an upwardly and inwardly extending lifting arm for picking up a door, means secured to the structure for supporting the door when closed, and means secured to the top of the door for engaging said door-supporting means, of means secured to the door to be engaged by the lifting arm of the carrier which is relatively wider than the lifting arm of the carrier, whereby the door may be readily and safely engaged by the lifting arm of the carrier without taking particular pains in effecting the operation.

7. The combination with a structure having a door opening, a removable door, a track extending horizontally above the door opening, a carriage traveling on said track and having two upwardly and inwardly extending lifting arms for picking up the door, means secured to the structure for supporting the door when closed, and hanger means secured to the top of the door for engaging the door supporting means on the structure, of lift plates secured to the front part of the door in position for said lifting

arms to engage the lower edge thereof and said plates having a relatively long recess in the lower edge thereof for receiving the lifting arms.

8. Apparatus substantially as set forth in claim 7, with the hanger means upon the door and said lift plates being secured together.

9. Apparatus substantially as set forth in claim 7, with said lift plates extending above the door, means for securing the hanger means to the portion of the lift plate above the door, and means extending over the top and behind the door and rigidly connected with the hanger means and plate to resist any rocking movement of the hanger means on the door.

10. Apparatus substantially as set forth in claim 7, with an angle iron on the top and rear side of the door, an extension from said lift plate projecting under the top plate of the angle iron, and the hanger means being located upon the angle iron, and bolts extending through the extension from the lift plate, the angle iron, and the bottom of the hanger means for securing them rigidly together.

11. The combination with a structure having a door opening, a removable door, a track extending horizontally above the door opening, and a detachable carrier travelling on said track and having two upwardly and inwardly extending lifting arms for picking up the door, of relatively wide hanger bars secured to the top of the door, relatively narrow upwardly and outwardly extending hanger hooks secured to the structure in position to receive the hanger bars and support the door, and lift plates secured to the upper front part of the door and having on their lower edges relatively long recesses in position to receive said lifting arms, the length of said recesses being relatively greater than the thickness of said lifting arms, whereby the apparatus may be satisfactorily operated without taking pains for accurate operation thereof.

12. Apparatus substantially as set forth in claim 11, with said lift plates and hanger means being rigidly secured together.

13. The combination with a structure having a series of door openings extending horizontally, a removable door for each opening, a track extending horizontally above the series of door openings, and a detachable carriage travelling on said track and having an upwardly and inwardly extending lifting arm adapted to pick up any door and remove it from its door opening and move it laterally to some other position and return it to door closing position, of a pair of relatively narrow upwardly and outwardly extending hanger hooks secured to the structure above each door opening, a pair of relatively wide hanger means secured to the top

of each door in position to engage and be supported by said hanger hooks when the door is closed, and a lift plate secured to the front side of each door and having a recess in the lower edge in position to receive the lifting arm, the length of said recess being relatively greater than the thickness of the

lifting arm, whereby with said carriage said doors may be easily and rapidly manipulated without requiring great pains in the 10 operation.

In witness whereof, I have hereunto affixed my signature.

ORVILLE F. SHATTUCK.
